UNITED STATES PATENT OFFICE

GEORGE RITTER, OF WOODBRIDGE, NEW JERSEY, ASSIGNOR TO THE BARBER ASPHALT COMPANY, OF PHILADELPHIA, PENNSYLVANIA, A CORPORATION OF WEST VIRGINIA

ROOF COVERING

Application filed September 21, 1925. Serial No. 57,486.

This invention relates to weather coverings for roofs and other exposed surfaces, while it has more particular reference to shingles of the flexible variety which are fabricated of 5 bibulous material saturated with bituminous substance and finished with a mineralized surfacing.

An object of this invention is to provide a self-aligning shingle which when laid in 10 overlapping rows affords a novel exposure which is both unusual and attractive.

Another object is to provide a novel configuration of shingle having a medially located tab at its lower edge which, when retroverted, 15 snugly pockets within opposed contiguous recesses of a pair of subjacent shingles whereby successively laid rows of such shingles correctly align and are evenly compacted with the major portion exposed.

20 Other objects and advantages will evidence themselves from the following description of one practical embodiment of this invention, as typically illustrated in the accompanying drawings; while the novel features thereof 25 are tersely defined as to subject-matter and scope by the appended claims.

In the drawings:—

Fig. I, is a plan view illustrative of the economical manner in which shingles embodying the present improvements are severed from standard width material.

Fig. II, is a top plan view of a fragment of a surface covered with the improved shingles; and,

35 Fig. III, is a section taken approximately on a plane as indicated by the arrowed lines III—III in the preceding view.

Referring more particularly to Fig. I of the drawings it will be observed that the individual shingles 4, are severed, in reverse relation, from a web or roll of sheet material 5, having a predetermined width to effect economical cutting. Each shingle unit 4 conveniently—though not essentially—comprises an 40 upper rectangular section 6 having the lower corners removed to provide right-angled recesses 7; an apron portion 8 having the upper and lower corners reversely curved at 9, 10, respectively; and a medially located rectangular tab 11 at the lower edge which is retro-

vertible along a crease 12 into underfolded relation with respect to the aforesaid apron 8, as well as for a purpose later on explained. It is noteworthy, at this point, that the radii for all of the curves 9, 10 is of the same lineal dimension in order to produce a regular pattern effect when the shingles 4 are laid. Furthermore it is to be explicitly understood that I do not limit myself to the particular configuration of apron 8, shown and described, as it may be made square, rectangular, polygonal or otherwise, in order to establish the desired pattern effect. It is preferable, however, that the section 6 be rectangular with the lower corners 7, 7 notched out in reverse 55 relation as shown, said recesses—when brought into contiguity—conforming in outline with the configuration of the retroverted tab 11 for a purpose hereinafter explained.

Shingles of the type above described are 70 laid as follows:—

A starting strip 13 is provided, at the requisite intervals, along one longitudinal edge with cut-outs or recesses 14 and it is secured to the roof or other surface boarding 15 by means of nails 16 and washers 17, applied adjacent the angular corners of said recesses, as clearly shown at the lower right hand of Fig. II. The washers 17, it will be noted, are thus placed so that one edge thereof projects beyond the edge of the shingle material through which the nails 16 are driven. On reference to Fig. III, it will be seen that the first or lower row of shingles 4 are consecutively laid with their respective underfolded tabs 11 inserted into the starter strip recesses or pockets 14, and that the vertical edges of said tabs are firmly clamped by the projecting portions of the washers 17, thereby establishing a substantial hold-down connection for the apron 90 portions 8. It will also be remarked that the shingles 4 are self-aligned by reason of the relatively large rectangular tabs 11 being snugly received in the recess pockets 14, aforesaid, and the vertical edges or sides of contiguous rectangular sections 6, 6 abutting. The laid shingles are successively secured immovably in place on the surface boarding 15 by nails 16—and washers 17—driven there-through adjacent the angular corners of the 95 100

right angled recesses 7, 7 as will be obvious from an inspection of Fig. II. Thus it will be seen that each shingle 4 is nailed down at two points, while the apron portion 8 thereof is securely clamped down by cooperation of a pair of subjacent nails 16 and washers 17. The second and successive rows of shingles 4 are similarly laid, but with the tabs 11 engaged in the recess afforded by contiguous right-angled recesses 7, 7, as is self-evident; while it will be observed that after the second row is laid, in the manner set forth, each individual shingle is nailed down at four points with the tab 11 clamped as aforesaid.

From the foregoing it is thought that the advantages inhering to the present invention will be clearly apparent, while it may be noted that a surface covered with the improved shingles is sixty-five per cent two-ply and of an unusually attractive appearance. Furthermore, by the use of round washers 17 they do not require any special pre-positioning, other than necessary for ordinary nailing, to afford the requisite projecting parts for tab clamping purposes.

Finally it will be readily recognized that the shingle illustrated fully justifies the features set forth as desirable, and while the particular embodiment described may be found economical to produce it is to be understood that the design of the apron portion 8 may be varied to suit individual tastes, without departing from the scope of this invention.

Having thus described my invention, I claim:

1. In a surface covering, a first row of shingles, each of which consists of a lower portion and an upper portion, the upper portion having parallel side edges contacting substantially throughout their extent with the side edges of the upper portions of adjacent shingles, the adjacent side edges of the lower portions of adjacent shingles being shaped to form pockets, each of which has a horizontal upper edge and side edges, and a second row of similar shingles overlapping the first row, the shingles of said second row being provided with tabs at their lower edges, said tabs having the configurations of the pockets and being turned under the shingles of the second row and lying within the said pockets in the plane of the shingles of the first row.

2. In a surface covering, a first row of shingles, each of which consists of a lower portion and an upper portion, the upper portion having parallel side edges contacting substantially throughout their extent with the side edges of the upper portions of adjacent shingles, the adjacent side edges of the lower portions of adjacent shingles being shaped to form pockets, a second row of similar shingles overlapping the first row, the shingles of said second row being provided with tabs at their lower edges, said tabs being turned

under the shingles of the second row and lying within the said pockets in the plane of the shingles of the first row, and means for retaining said tabs within the plane of the shingles of the first row, said means comprising fasteners passing through the underlying shingles and provided with portions extending over the edges of the pockets formed by the underlying shingles.

3. In a surface covering, a first row of shingles, each of which consists of a lower portion and an upper portion, the upper portion having parallel side edges contacting substantially throughout their extent with the side edges of the upper portions of adjacent shingles, the adjacent side edges of the lower portions of adjacent shingles being shaped to form pockets, each of which has a horizontal upper edge and side edges, and a second row of similar shingles overlapping the first row, the shingles of said second row being provided with tabs at their lower edges, said tabs having the configurations of the pockets and being turned under the shingles of the second row and lying within the said pockets in the plane of the shingles of the first row, and means for retaining said tabs within the plane of the shingles of the first row, said means comprising fasteners passing through the underlying shingles and provided with portions extending over the edges of the pockets formed by the underlying shingles.

In testimony whereof I have hereunto signed my name at Maurer, N. J., this 15th day of September, 1925.

GEORGE RITTER.
